UNITED STATES PATENT OFFICE.

CARL A. BRINK, OF PROVIDENCE, RHODE ISLAND, ASSIGNOR TO UNIVERSAL WINDING COMPANY, OF BOSTON, MASSACHUSETTS, A CORPORATION OF MASSACHUSETTS.

COP-HOLDER.

1,317,545.

Specification of Letters Patent. Patented Sept. 30, 1919.

Application filed March 18, 1918. Serial No. 223,141.

To all whom it may concern:

Be it known that I, CARL A. BRINK, a citizen of the United States, residing at Providence, in the county of Providence, State of Rhode Island, have invented certain new and useful Improvements in Cop-Holders, of which the following is a specification.

My invention relates to cop-holders for winding, braiding or other textile machines, and consists particularly of improvements in the construction and method of operation of the same. My improved cop-holder is intended for use with either paper cop-tubes and quills, or wooden bobbins and spools, and the object of the improvement is to provide a simple and efficient means for gripping the bore of the tube or bobbin to secure it rotatively on its spindle or mandrel.

The manner and means for carrying out the improvement are fully described in the following specification, illustrated by the accompanying drawings, in which like reference characters represent like parts. In the drawings:

Figure 1 is a side view of a spindle or mandrel showing a cop-tube applied thereto to illustrate my improved means for securing it rotatively therewith;

Fig. 2, a detail view in perspective of one of the longitudinal blades employed for holding the cop-tube rotatively with the spindle;

Fig. 3, an end view of the cop-holder;

Fig. 4, a sectional view on the line $x-x$ of Fig. 1; and

Fig. 5, a similar view taken on the line $y-y$ of Fig. 1.

Referring first to Fig. 1, 2 designates a cylindrical spindle or mandrel, which as here shown is provided at one end with a reduced shank 3 formed with screw-threads at 4 to adapt it to be attached to the end of a winding-shaft or other rotating element of the machine. C represents the cop-tube which fits over the spindle 2, and the means for securing it rotatively therewith comprises essentially a plurality of longitudinally-extending spring-blades 5. In the present embodiment of the invention the spindle 2 is illustrated as being formed with four longitudinal slots 6 for receiving the spring-blades 5. My improvement is not limited as to this particular, however, as in some instances it has been found preferable

to use three blades instead of four. The slots 6 in the spindle 2 are relatively shallow, and the blades 5 fit snugly therewith at their opposite ends. At the inner end a collar 7 is slipped on over the spindle 2, after the blades 5 have been placed in their slots 6, and is secured thereto by suitable means, such as the set-screw 8, to hold the blades in place. At their opposite ends the blades 5 are bent down in hook-portions 9, see also Fig. 2, which are adapted to hook into a recess 10 at the end of the spindle 2. The recess 10 is preferably formed by counter-boring the spindle 2 to form an undercut, beveled shoulder, and this end of the spindle is also bored axially and threaded as shown at 11. A screw 12 is adapted to be inserted in the threaded bore 11 of the spindle 2 and the under side of its head 13 is beveled at 14 to correspond with the beveled recess 10. After the blades 5 have been placed in their slots 6, with their hooked ends 9 in position against the undercut recess 10, the screw 12 is screwed into place to set its beveled head 13 against the ends 15 of the hooks. In this way the blades are held snugly in place at their outer ends while their inner ends are retained in the slots 6 by means of the collar 7. It will be noted from reference to Fig. 3 that the bore 16 of the collar 7 is slotted at 15 opposite the slots 6 in the spindle 2. This provides a slight clearance for the blades 5 to allow a sliding movement at their inner ends for a purpose as later explained.

Referring now particularly to Fig. 2, each blade 5 is constructed of relatively flat sheet-metal and is twisted spirally on a longitudinal axis. This twisting of the blade 5 forces one of its lateral edges upwardly at 17 an angle to its main plane as shown at a , while the opposite edge is inclined upwardly at b . The purpose of this twisting or distorting of the blades 5 is to provide sharp edges adapted to project radially outward from the periphery of the spindle 2 to engage the interior of the bore of the cop-tube when the latter is slipped onto the spindle. As shown in Fig. 4, one edge a of the blade 5 projects outwardly in one direction 18 to adapt it to bite into the interior surface of the tube C to hold the latter from movement on the spindle in the direction indicated by the arrow d . The opposite, up-turned edge b of the blade 5 projects into 19

the bore of the cop-tube at a reverse angle, as shown in Fig. 5, to prevent the tube from turning on the spindle 2 in the direction indicated by the arrow *e*. That is to say, one edge *a* of the blade 5 holds the tube C rotatively against the thrust in one direction, while the other edge *b* holds it from turning in the opposite direction. In some cases, where it is only required to secure the tube 10 on the spindle against turning movement in one direction, one side only of the blade 5 is formed with an upturned edge. In most cases, however, it is preferable to provide means for securing the tube from turning movement in both directions, and the present construction is adapted for this purpose.

The method of operation of my complete device is as follows: After the blades 5 have 20 been assembled in the slots 6 on the spindle 2, and the collar 7 and screw 12 set in place to retain them in position, no further adjustment of the parts is required. It is not necessary that the tube C fit the bore of the 25 spindle 2 exactly since the blades 5 are more or less self-conforming. Usually, there is a slight clearance between the periphery of the spindle and the bore of the tube C, and the blades 5 act as centering-devices to hold 30 the tube concentric with the axis of the spindle. That is to say, their inherent spring-tendency adapts them to fit tubes or bobbins having bores of slightly varying diameters, and renders them capable of holding 35 the tube in concentric relation with the spindle which it surrounds. In applying the tube C to the cop-holder, it is only necessary to slide it onto the spindle 2 and the spring-blades 5 will contract slightly during 40 this action. As the intermediate portion of the blades 5 contract into their slots 6, their inner portions will slide to a slight extent through the slots 15 in the collar 7. At the same time the spring-tendency of the blades 45 will cause their upturned edges *a* and *b* to bite into the material of the tube, or, in other words, to grip its bore as shown in Figs. 4 and 5. After the tube C has been slid clear onto the spindle 2, with its inner end abutting the collar 7, it is held firmly in place by 50 the sharp edges of the spring-blades 5. On the other hand, if it is at all times adapted for convenient removal by merely sliding it off from the spindle, the blades 5 contracting 55 slightly under this action. When the spindle 2 is rotated to wind on the yarn to build up a cop, such as a cylindrical package indicated by dot-and-dash lines A in Fig. 1, the tube C will be turned with it, 60 while the blades 5 prevent any slippage under resistance to its rotation. That is to say, any thrust against the tube in either direction is met by the engagement of the upturned edges *a* and *b* of the blades 5 with 65 its interior surface, and the stronger the re-

sistance, the firmer the blades will bite into the bore of the tube. In this manner my improved holding-means provides a very secure engagement between the cop-tube and the spindle which is automatically effected 70 without requiring the adjustment of expansion-elements or other devices.

My improved device is particularly adapted for use on machines for winding large packages of relatively heavy material 75 since it provides a firm grip between the cop-tube and the winding-spindle to prevent slippage under severe stresses. Heretofore, it has been the usual practice to employ expandable spindles or arbors for winding machines, but these require a complication of mechanism, besides necessitating manual adjustment each time a new tube is applied or the finished cop doffed. With my present arrangement it is only necessary to slide the 80 tube onto the spindle, when the gripping-means take hold automatically. Also, in doffing the cop, it is only required to slide the tube off from the end of the spindle without the previous release of dogs, springs or 85 other fastening-means. It is also to be noted that my improved cop-holder is extremely simple in construction, providing for ease and economy of manufacture, and the parts are held together through an ingenious arrangement which renders the 90 whole device practically proof against derangement or getting out of order.

I am aware that it is old in the art to make use of compressible spring-members 100 to grip the interior of cop-tubes, spools or the like to secure them in place on spindles or other mandrels. It is believed, however, that the construction herein shown has distinctive features over and above what has 105 previously been proposed, and that my novel arrangement of the spring-blades and their method of operation constitute a meritorious improvement in the art to which the invention belongs.

Various modifications might be made in the form and structure of the parts of the device without departing from the spirit or scope of the invention; therefore, without limiting myself to the exact embodiment 115 shown and described, what I claim is:—

1. In a holder for cop-tubes, bobbins, spools or the like, the combination with a mandrel, of spring-blades extending longitudinally thereof, said blades being relatively flat and twisted spirally on a longitudinal axis to provide upturned edges adapted to engage the interior of the tube or bobbin to secure it rotatively with the mandrel.

2. In a holder for cop-tubes, bobbins, spools or the like, the combination with a spindle formed with longitudinally-extending slots on its periphery, of spring-blades secured in said slots, said blades being rela- 130

tively flat and twisted spirally on a longitudinal axis to provide upturned edges projecting radially outward from the periphery of the spindle to adapt them to bite into the bore of the tube or bobbin when the latter is slid into position thereover.

5 3. In a holder for cop-tubes, bobbins, spools or the like, the combination with a spindle having longitudinal slots on its periphery, of relatively flat spring-blades held at their ends in said slots with their intermediate portions twisted laterally to upset their edges in angular planes whereby they project outwardly from the periphery of the 10 spindle to engage the bore of the tube or bobbin to secure it rotatively thereon.

15 4. In a holder for cop-tubes, bobbins, spools or the like, the combination with a spindle having a recessed end, of a plurality 20 of spring-blades bent down at their outer ends to hook into the recess in the spindle and twisted spirally throughout their intermediate portions to provide upturned lateral edges extending the greater part of 25 their length, and means to retain the inner ends of the blades in spaced relation around the spindle.

5 5. In a holder for cop-tubes, bobbins, spools or the like, the combination with a 30 spindle formed with a recessed end, of longitudinally-extending blades having their outer ends bent down and hooked into the

recess in the spindle and their intermediate portions twisted spirally to provide upset, lateral edges, and a collar held in position 35 on the spindle surrounding the inner ends of the blades to maintain them in a spaced relation therearound.

6. In a holder for cop-tubes, bobbins, spools or the like, the combination with a 40 spindle formed with a recessed end, of a plurality of longitudinally-extending blades formed with their intermediate portions twisted spirally to provide upset, lateral edges, and having hooks at their outer ends 45 engaging the recess in the spindle, a stud screwed into the end of the spindle to secure the hooked ends of the blades in place, and means for holding the inner ends of the blades in spaced relation around the 50 periphery of the spindle.

7. In a holder for cop-tubes, bobbins, spools or the like, the combination with a spindle having longitudinally-extending slots on its periphery and a recess at its end, 55 of relatively flat spring-blades twisted spirally on a longitudinal axis, and seated in the slots with their outer ends hooked into the recess in the spindle, and a collar secured on the spindle surrounding the inner ends 60 of the blades to hold them in spaced relation therearound.

In testimony whereof I affix my signature.
CARL A. BRINK.
